UNITED STATES PATENT OFFICE.

MARTHA R. HARRISON, OF JERSEY CITY, NEW JERSEY.

DESIGN FOR A DOLL.

Specification for Design.

Patented Jan. 11, 1916.

Application filed September 26, 1914. Serial No. 863,770. Term of patent 14 years.

To all whom it may concern:

Be it known that I, MARTHA R. HARRISON, a citizen of the United States, residing at Jersey City, in the county of Hudson and State of New Jersey, have invented a new, original, and ornamental Design for Dolls, of which the following is a specification, reference being had to the accompanying drawing, forming part thereof.

The figure is a perspective of a doll embodying my design, which is the representation of a very young nude infant, rather fat and rotund in general outline, and with its

head, arms, hands, limbs and feet occupying correlated positions constituting a general pose, suggestive that the infant is making a strenuous but ineffectual effort to change its general position.

I claim—

The ornamental design for a doll, as shown and described.

MARTHA R. HARRISON.
